UNITED STATES PATENT OFFICE.

EDWARD KNAPP, OF ST. LOUIS, MISSOURI, ASSIGNOR OF ONE-HALF TO
GEORGE D. BARNARD, OF SAME PLACE.

RULING-MACHINE GATE.

SPECIFICATION forming part of Letters Patent No. 329,458, dated November 3, 1885.

Application filed May 8, 1885. Serial No. 164,839. (No model.)

To all whom it may concern:

Be it known that I, EDWARD KNAPP, of St. Louis, Missouri, have made a new and useful Improvement in Ruling-Machine Gates, of 5 which the following is a full, clear, and exact description.

In ruling paper this difficulty is experienced: the sheets to be ruled are often not cut squarely at their ends, and it becomes 10 necessary to adjust the gate to suit the angle of the sheet, and when once adjusted the supervision must be continued, for the angle of the sheet ends may change, and in practice is liable to change at irregular intervals, and 15 if the gate is not promptly readjusted with every change in the sheets the ruling is incorrectly done and the paper spoiled. To obviate the need of such superintendence and to provide a self-adjusting gate is the aim of the 20 present improvement.

The annexed drawings, making part of this specification, exhibit only that portion of a ruling-machine that is essential to an understanding of the improvement.

25 Figure 1 is a view in perspective of the gate detached from the supporting-arm. Fig. 2 is a plan of the gate. Fig. 3 is a section on the line 3 3 of Fig. 5. Fig. 4 is a cross-sectional view of the gate, and Fig. 5 is a plan 30 showing the improved gate in position. The set-screw for holding the gate in the block is not shown.

The same letters of reference denote the same parts.

35 A, Fig. 5, represents that portion of a ruling-machine with which the gate is more immediately connected. It is of the customary form, and is operated in the customary manner, saving as modified by the improvement in 40 question.

B represents the bar or shaft, to which the gate C is attached.

The principal feature of the gate C is pivoting the part c, which comes in contact with 45 the sheets being ruled, in the holder c' so that the part c can be swung horizontally and to a sufficient degree for the purpose in view. To this end the part c, in prac-

tice a light strip, substantially as shown, is, by means of the set-screw c², held in the block 50 c³, which in turn is journaled at c⁴ in the holder c'.

The holder c' consists, mainly, of the cross-bar c⁵, the adjustable stops c⁶ c⁸, and the arm c⁷. The stops c⁶ are in the form of a screw, 55 provided with the head c⁹ and the shoulder c¹⁰, which come, respectively, upon opposite sides of the part c, and according to the position of the stop in the cross-bar is the limit of the vibration of the part c. If the stop is 60 screwed farther into the cross-bar, the part c can be swung through a longer arc, and if the stop is unscrewed so as to bring the shoulder farther away from the cross-bar, the part c 65 cannot be swung so far, and by unscrewing the stops so as to bring them abreast the journal c⁴, as in Fig. 2, the part c can be held rigidly in the holder c'.

The holder c', carrying the part c, can be made adjustable toward and from the bar B, 70 and preferably as follows: The arm c⁷ is slotted at c¹⁰. An arm, c¹¹, is screwed to the bar B. The arm c⁴ is passed onto the arm c¹¹, and by means of the clamp-screw c¹² the two arms c⁷ c¹¹ are fastened together, and according to 75 the position of the arm c⁷ upon the arm c¹¹ is the position of the part c with reference to the bar B.

Fig. 5 illustrates the operation of the improvement. The forward edge, d, of the sheet 80 D is supposed to be out of square with the side d'. As the edge encounters the part c, the part c turns on its pivot until it coincides with the edge d, after which it rises and falls in the ordinary manner—that is, the part c is 85 sufficiently light and is so sensitively pivoted as not to offer any obstruction to the sheet until the entire edge of the sheet bears against the part.

The part c may be termed the "gate proper."

I desire not to be limited to any special mode of adjusting the gate in its holder so that it shall swing horizontally, as described. The method shown, however, is considered the 95 most desirable.

I claim—

1.	The combination of the pivoted part <i>c</i> , the holder <i>c'</i> , the arm <i>c¹¹</i> , and the bar <i>B</i> , substantially as described.	3. A ruling-machine gate pivoted in its holder to swing horizontally, as described.
5 2.	The combination of the pivoted part <i>c</i> and the holder <i>c'</i> , having the stops <i>c⁶</i> , substantially as described.	Witness my hand. EDWARD KNAPP.
